INSULATOR TIE FOR LINE CONDUCTORS

Ralph D. Pyle, Pleasant Hills, Pa., assignor to
 Copperweld Steel Company, Glassport, Pa., a
 corporation of Pennsylvania

Application March 24, 1945, Serial No. 584,536

8 Claims. (Cl. 174—173)

1

This invention relates to a tie for securing transmission and distribution line conductors to pin type and spool insulators.

Various forms of insulator ties have been proposed heretofore for securing conductors at their points of support. All such ties have been open to certain objections and it is accordingly an object of this invention to provide an improved tie which is simple and easy to apply and which largely eliminates the human element and personal skill required for application. The tie is effective in securing the conductor in such a manner as to minimize the danger of fatigue failure resulting from vibration and to eliminate chafing of the line wire due to looseness of the tie.

In a preferred embodiment the invention comprises a pair of hard-drawn preformed helical reinforcing wires, adapted to be applied to the conductor, having loops formed therein adapted to engage opposite sides of an insulator, whereby the insertion of a binding wire through the loops and the twisting together of its ends serve to complete the tie and securely anchor the conductor to the insulator. The reinforcing wires when applied to the conductor have a relatively tight fit on the conductor since the inside diameter of the helix is substantially the same as the diameter of the line conductor on which it is applied.

The details of the invention will be made clear during the following complete description and explanation which refer to the accompanying drawings illustrating a preferred embodiment and certain modifications. In the drawings

Figure 1 is a plan view showing one form of tie;

Figure 2 is a side elevation thereof;

Figure 3 is a partial elevation of one of the reinforcing wires;

Figure 4 is a partial plan view thereof;

Figures 5 and 6 are views similar to Figures 3 and 4 showing a modified form;

Figure 7 is an end elevation of the modified form;

Figures 8 and 9 are views similar to Figures 1 and 2 showing a further modified tie;

Figure 10 is an elevation of the reinforcing wire used in the last mentioned modification;

Figure 11 is a plan view of a side tie embodying the invention; and

Figure 12 is an elevation thereof with parts in section.

Referring now in detail to the drawings, a transmission or distribution line conductor 10 is adapted to rest in a groove 11 in the top of an insulator 12. The insulator is adapted to be

2

mounted on a pin secured to a pole or a cross-arm carried thereby. A pair of substantially identical preformed helical reinforcing wires 13 and 14 are applied to the conductor 10. The reinforcing wires have loops 15 projecting therefrom intermediate their ends. The wires 13 and 14 are applied to the conductor in spaced relation thereon so that the loops 15 will engage the sides of the insulator adjacent the top, as shown in Figure 2. The wires 13 and 14 overlap each other except for a short distance inwardly from the ends.

When the wires 13 and 14 have been applied to the conductor the latter may be secured to the insulator by a binding wire 16. For this purpose a suitable length of wire has its ends inserted through the loops 15 and twisted together at 17.

It will be appreciated that the tie described above has the advantage that no forming of wire is required on the job except the twisting together of the ends of the binding wire. This operation may readily be performed with a pair of pliers, although special tools may be used to facilitate this twisting of the binding wire. A further advantage is that the reinforcing wires space the line conductor away from the bottom of the insulator groove and prevent any chafing action between the line conductor and the insulator. Also the reinforcing wires being preformed have a firm grip on the conductor insuring against chafing of the conductor by said reinforcing wires.

The depth of the loops 15 should be such that when the binding wire is tightened, the line conductor with the reinforcing wires thereon will be held firmly in the insulator groove without bending the conductor over the sides of the insulator. The width and design of the loops, furthermore, should be substantially equal to the pitch of the helix so that the wire on each side of the loop is a continuation of the same helix.

Figures 5, 6 and 7 illustrate a modified form of reinforcing wire 18 which is generally similar to the wires 13 and 14 except that, instead of an open loop 15, it has a closed loop or eye 19 intermediate the ends thereof. It will be apparent that this form of reinforcing wire functions in the same manner as those shown in Figures 1 through 4. It is hardly necessary to state that the helical portions or the reinforcing wire obtain a tight grip on the line conductor by friction so as to prevent longitudinal slippage of the conductor relative to the insulator.

Figures 8 through 10 illustrate a further modi-

fication of preformed helical reinforcing wire 28. This form of wire differs from those described above in that it has a closed loop or eye 21 adjacent one end. In securing a conductor 10 to an insulator by this form of reinforcing wire, two wires are applied with their eyes engaging opposite sides of the insulator and the adjacent portions of the wires in overlapping relation. The binding wire 16 is then applied by inserting its ends through the eyes 21. In this modification the conductor is again spaced away from the insulator to insure against chafing. Furthermore, it is evident that the resistive pressures on the line conductor are confined to the section over the insulator and are reduced by the bearing of the reinforcing wires on the insulator.

Figures 11 and 12 show a side tie for securing the conductor 10 to the insulator 12 in the circumferential groove 12a thereof. This tie, like that shown in Figures 8 and 9, requires two reinforcing wires 20, the only difference being that the eyes 21 thereof project laterally from the conductor instead of downwardly. A binding wire 22 has its ends brought around the insulator from the side opposite that on which the conductor is disposed, and passed through the eyes 21. The ends of the wire 22 are then bent back on themselves, taken back around the insulator and twisted together as at 23, to complete the tie.

The invention is characterized by an important advantage in that the preformed helical reinforcing wires constitute the connection from the conductor to the binding wire so that there is no contact between the latter and the line conductor. This overcomes the danger of chafing of the line conductor by the binding wire which is one of the faults of ties made entirely by hand. Such ties when improperly applied, or if they become loose due to vibration, can cause chafing of the line conductor. The personal skill or human element involved in applying hand-wrapped ties is largely eliminated by this improved type of tie.

A further advantage is the fact that the loops in the reinforcing wires may be properly dimensioned to give just the right amount of down pull, 45 without causing any localized bending of the line conductor which would tend to hasten fatigue failure. The use of two reinforcing wires to form the tie is an advantage in that they can readily be applied to the conductor so that insulators of various sizes may be accommodated by the loops formed by the wires.

Although I have illustrated and described but a few preferred embodiments of the invention, it will be understood that changes in the details thereof may be made without departing from the spirit of the invention or the scope of the appended claims.

I claim:

1. A tie for securing a line conductor to an insulator comprising two separate substantially identical, hard-drawn, preformed, helical, reinforcing wires adapted to be wrapped around the conductor, said wires being thereby effective to secure a tight frictional grip on the conductor, each wire having an offset loop formed therein, the wires being disposed on the conductor one on each side of the insulator, in partly overlapping relation, their loops engaging opposite sides of the insulator, and a binding wire extending around the insulator and through the loops of said reinforcing wires to secure the latter to the insulator.
2. An insulator tie as defined by claim 1 wherein in said loops are located intermediate the ends of said wires.
3. An insulator tie as defined by claim 1 wherein in said loops are U-shaped.
4. An insulator tie as defined by claim 1 wherein in said loops are substantially closed.
5. An insulator tie as defined by claim 1 wherein in said loops are closed and located intermediate the ends of said reinforcing wires.
6. An insulator tie as defined by claim 1 wherein in said loops are substantially closed and located at one end of each of said reinforcing wires.
7. An insulator tie as defined by claim 1 wherein in said loops are U-shaped and located intermediate the ends of the wires.
8. A tie for securing a line conductor to an insulator comprising two separate substantially identical hard-drawn, preformed, helical, reinforcing wires wrapped around and frictionally engaging the conductor, each wire having an offset loop formed therein, the wires being wrapped on the conductor in partly overlapping relation, with their loops engaging opposite sides of the insulator, and means engaging said loops and securing said reinforcing wires and said conductor to the insulator.
